UNITED STATES PATENT OFFICE.

AUGUSTE J. PARIS, JR., OF BRADFORD, PENNSYLVANIA.

PROCESS OF DISTILLING SOLIDS AND LIQUIDS AND OF CRACKING SOLIDS, LIQUIDS, AND GASES.

1,392,788.

Specification of Letters Patent.

Patented Oct. 4, 1921.

Application filed May 3, 1915. Serial No. 25,403.

To all whom it may concern:

Be it known that I, AUGUSTE JEAN PARIS, Jr., a citizen of the United States, residing in Bradford, county of McKean, and State 5 of Pennsylvania, have invented a certain new and useful Process of Distilling Solids and Liquids and of Cracking Solids, Liquids, and Gases, of which the following is a specification.

10 This invention is a process of distilling solids and liquids and of cracking solids, liquids and gases, and the objects of the invention, speaking generally, are to distil said liquids and solids under conditions 15 which enable the pressures, either plus or minus, and the temperatures to be accurately and effectively controlled, and to permit of the cracking of the various materials under similar conditions of control.

20 Heretofore, serious difficulties have existed in connection with the cracking of hydrocarbons, because of the fact, among others, that the separated carbon accumulated and caked at the bottom of the still, 25 the point at which the heat for distillation is applied, and eventually resulted in the burning out of the bottoms of the stills or retorts.

Moreover, even in the ordinary processes 30 of distillation, where cracking is not specially aimed at, there is usually some deposit of carbon and always a deposit of other residues, which occasion the same disadvantages referred to in connection with 35 the cracking processes.

The present invention overcomes the disadvantages referred to, as well as others, and embodies, as one of its salient features, a still, or other receptacle, wherein the solid, 40 liquid, or gaseous material is treated, in which still is contained a molten mass of metal, preferably lead, through which the materials treated are passed or brought into contact with, depending on the particular 45 operation being performed.

Speaking generally, the advantages of employing a molten bath of metal, for the purposes specified, are as follows: First, the bottom of the still is kept entirely free 50 from any deposit of carbon or other residues, this result being effected, mainly, because of the fact that the agitation of the molten metal, through boiling, keeps the bottom of the still or retort clean; the separated material, such as carbon or residues,

being of less specific gravity than the bath, flows to the surface of the latter, and, in its passage through the metal becomes disintegrated, that is to say, is kept from caking; second, in the cracking or similar operation, 60 there is an intimate and extended contact of the material treated with the molten metal, thereby allowing ample time for the completion of the chemical reactions desired; third, the temperature can be uniformly controlled at the same degree as, or above that, of the molten bath employed, and this can be easily effected automatically; this can be accomplished by regulating the quantity of heat applied to the still, 65 or by keeping the quantity of heat constant, and regulating the quantity of liquid or gas admitted to the still or retort; fourth, a uniform and predetermined pressure can be readily secured at the bottom of the still, 70 by regulating the height or column of the bath, and, fifth regardless of the pressure at the bottom of the still, the pressure at the top, above the molten metal, may be varied as desired, *i. e.*, at, above, or below, atmospheric pressure. Advantages of the process, other than those enumerated, will appear from the hereinafter description.

As examples of the liquids which may be operated upon, though not the exclusive 85 ones, may be mentioned petroleum and its distillates, either individually or collectively, and oils obtained from the distillation of coal, shale, peat, lignite, and similar materials. Other liquids which may be 90 treated will readily suggest themselves to those skilled in the art, such, *e. g.*, as turpentine, tar, asphalt, etc.

Among the numerous gases which may be treated may be mentioned coal gas, oil gas, 95 natural gas, and gases obtained from the distillation of wood, lignite, and similar materials.

Among the solids which may be operated upon may be mentioned paraffin and other 100 waxes, asphalt, resin, and various other solids which may be dissolved or otherwise liquefied. Paraffins may be readily converted into olefins through the employment of the present invention.

105 Features of the process, and their advantages, other than those referred to, will be apparent from the hereinafter detailed description taken in conjunction with the accompanying drawings.

In the accompanying drawings, one form of apparatus is shown which may be successfully employed in practising the several processes, but said apparatus is merely typical, and the processes, as will be obvious to those skilled in the art, may be carried out in other forms of apparatus.

Referring to the drawings, Figure 1 shows, partly in section and partly in elevation, a complete apparatus for the treatment of gases, liquids or solids.

Fig. 2 is a sectional view of a still which may be advantageously employed in the manufacture of lampblack, and

Fig. 3 shows a simple type of still or retort for distilling purposes.

In the drawings, A is a retort or still, B a liquid separator connected with the outlet therefrom, C a pressure or vacuum pump in the system, D a condenser, and E a receiving chamber for the condensates, wherein the non-condensable gases are separated. Still A contains a molten metal or bath, preferably of lead, a, and it is manifest that the column of molten metal may be of any desired height thereby providing means for controlling the pressure within the still, particularly at the bottom thereof.

A main b is provided for introducing oil or other liquid into the still through branch pipe b', controlled by valve b''. Main b may be provided with a preheater b'', which, as shown, is in the form of a coil which may be heated by a gas burner b', which receives its supply from a branch pipe b'' leading from a gas main G, said branch pipe b'' being provided with a regulating valve b''. It will be noted that branch pipe b' extends within the molten metal. Main b is also provided with another valve controlled branch b'', having a discharge outlet b'' located above the surface of the molten metal, whereby oil or other liquid may be delivered on top of the molten metal, instead of within the body of the metal.

Another feed main c is provided for introducing gas into the still or retort, beneath the surface of the molten metal, said pipe c being provided with a pre-heater c', heated by a burner c'' which receives its supply of gas from a valve-controlled pipe c''. The downtake c'' from branch c is provided with a valve c'', said downtake pipe having its outlet c'' located below the surface of the molten metal.

Still or retort A may be heated in any desired manner, but I have shown a gas-heater H, which received its supply from gas main G, said main being provided with a manually operated valve h and a thermostatically controlled valve h''. A well known type of thermostat is illustrated for controlling the supply of gas to the burner H, embodying an expandible member h'' within the still, which, when the temperature of

the still reaches a predetermined point, completes a circuit through contact point h'', battery h'', wires h'' h'', to the electro-magnets h'', which operate bellcrank lever h'' to seat valve h'', thereby diminishing, or shutting off, the supply of gas until the temperature is reduced to the desired point, whereupon expandible member h'' by its contraction, causes a break in the electric circuit, with the result that valve h'' reopens automatically. Similar thermostatic controlling devices may be employed to regulate the quantity of material admitted to the still through pipes c and b. In pipe c, I have shown, diagrammatically, a valve s and thermostatic control s''. In pipe b I have shown similar parts s'' and s'''. As the temperature of the still rises above a predetermined point, valve s or s'' automatically opens and admits a larger quantity of material to the still.

Still A may be provided with the customary regulating devices, such as a pyrometer d, and a pressure or vacuum gage d', and feed mains b and c may also be provided with pressure or vacuum gages d'' and d''', respectively. If the materials introduced through the pipes b and c are to be introduced below the surface of the molten bath, they will naturally be under pressure and the gages d'' and d''' will then be pressure gages, but if such materials are to be introduced above the surface of the molten metal, these gages may be vacuum gages.

Main c has a downtake e, provided with a valve e'', the outlet e'' being positioned above the surface of the molten metal in the still. This pipe may be employed for blowing out of the still the lampblack or other similar products which may separate at the surface of the molten metal, or may be used to carry away the vapors which accumulate at the top of the still.

The temperature at the top of the still may be controlled by water or other refrigerating liquid entering through main g, through valve g'', and nozzle g'', by which it is sprayed on the top of the still, and flows into trough g''', whence it is drawn off through waste-pipe g''.

The separator or trap B is of any well known type, and the liquid or liquids which accumulate therein may be drawn off through valve i. Separator B has a direct connection with vacuum or pressure pump C, through a hand-controlled valve i'' and the flap valve i''', the flap in this valve being so arranged as to permit the gases to flow to pump C, but precluding their return. The outlet from pump C is connected to the inlet of coil D' of condenser D, a flap valve i'' precluding the return of gases to the pump, and a pressure or vacuum gage d'' indicating the pressure, plus or minus, at

which the gases enter the condensing coil. A by-pass C', having controlling valves j , j' , may be introduced in the system, whereby the gases from separator B may be passed directly into the condensing coil D', *i. e.* without passing them through pump C.

Condenser D is provided with an inlet and an outlet k , k' , respectively, for the refrigerating medium, although it will be understood that coil D' may be cooled in other ways, as *e. g.*, by an expanding gas. The outlet of coil D' leads to the separator or receiving chamber E, wherein the condensed liquids accumulate, from which they may be withdrawn through valve j^2 . The gases which are not condensed pass from the top of separator E into pipe l, which is provided with a pressure or vacuum gage l' , and a manually controlled valve l^2 . It will be understood that the pressure on the system may be controlled, as desired, by regulating the valve l^2 . In other words, by controlling the flow of the residual gases through said valve, a back pressure may be produced upon the system.

Referring to the apparatus shown in Fig. 2, which is especially adapted for making lampblack, A' is the still or retort containing the molten lead or other metal α' , heated by gas-burner H' or other suitable heating means. It has a liquid or gaseous inlet m , dipping below the surface of bath α' , in which may be located a pre-heater m' , hand valve m^2 , and pressure or vacuum gage m^3 . It may also, if desired, be provided with a stirrer, J, operated from a pulley K, for keeping the molten metal agitated. Its outlet n leads to a receptacle or chamber I, wherein lampblack is deposited. Chamber I is provided with a valve o , normally open, but which may be closed to permit the removal of the lampblack which accumulates in the bottom of the chamber without interfering with the operation of the apparatus. At the top of chamber I is an inclined baffle p , which deflects the separated lampblack, and an outlet pipe q for the escape of residual gases. Retort A' is provided with a gas inlet pipe q' , for blowing the separated lampblack out of the retort into chamber I. Pipe q' may, if desired, be supplied with a pre-heater, similar to those heretofore described, consisting of a coil q^2 , heated by a gas-burner q^3 . The burner H' may be thermostatically controlled the same as burner H, previously described, and the customary accessories, such as gages, pyrometers, etc., applied thereto.

Referring to Fig. 3, which illustrates an apparatus particularly adapted for distillation, A² is a retort or still, in the bottom of which is the molten metal or lead α^2 , kept in its molten condition by gas-burner H², or other suitable heating means. The re-

tort is provided with a suitable inlet r and outlet r' . Still A² may also be provided with some of the accessories, previously described in connection with still A, such as a thermostat, pre-heater, gages, and pyrometer. The upper part of the still A² may, moreover, be coiled in the manner shown with reference to the still A.

Having fully described the apparatus, and its general mode of operation, as well as a number of the materials which may be treated, brief reference will be made to a few of the specific processes which may be practised.

Assuming a liquid, *e. g.*, crude petroleum, or any of its fractions, is to be distilled, it may be introduced into still A through main b and branch b' onto the surface of the molten metal. This operation may be similarly carried out in retort A², Fig. 3. By manipulating the apparatus, as described, and desired pressure, from plus to minus, may be produced in the top of the still. The various products of distillation may be separated, as described, it being understood that a plurality of separators B, condensers D and traps E may be used if desired, only single ones having been shown to avoid undue complication of the drawing.

If it be desired to "crack" or polymerize a liquid (or dissolved solid), it may be introduced through main b and branch b' beneath the surface of the molten lead. The resulting products pass off and may be collected or separated as described.

In making lampblack, *e. g.*, the liquid hydrocarbon or gas may be introduced beneath the surface of the lead through pipe m (Fig. 2), and the separated carbon blown into chamber I by a suitable blast of gaseous fluid, pre-heated if desired, introduced through pipe q' (Fig. 2) or branch pipe e of main C (Fig. 1). In this and similar processes, the top of the still or retort may be advantageously cooled by water or other refrigerant supplied by rose g^2 , Fig. 1.

The foregoing processes are merely illustrative, since the broad invention resides in the manner in which the temperature and pressure of various chemical operations may be accurately controlled, and different pressures and temperatures obtained in the bottom and top, respectively, of the still or retort. Accordingly, various processes, other than those described, as well as modifications and variations thereof, to meet the exigencies of any particular process, will readily suggest themselves to those skilled in the art. That is to say, the processes outlined are typical and suggestive, only, and do not preclude the application of the broad principles disclosed to processes involving analogous operations.

When the still is not in use, the molten lead may be drawn off through pipe L into

any suitable receptacle (adapted to be heated). The receptacle may then be elevated, and, when it is desired to further use the still, the lead may be remelted, and allowed to flow into the still by gravity.

5 Any suitable combinations of metals or alloys may be used in the still, for specific purposes, in lieu of the lead bath.

Having thus fully described the invention, 10 what I claim as new, and desire to secure by Letters Patent, is:

1. Increasing the illuminating value of natural gas by converting the paraffins into olefins by bringing said gas into contact 15 with a molten bath of metal.

2. The process of distilling hydrocarbons, which consists in bringing them in contact with molten metal, producing a partial vacuum by exhaustion at the upper part of the 20 still and cooling the upper part of the still externally.

3. The process of altering the composition of petroleum distillates which consists in introducing the distillates under pressure into a metal bath contained in a still 25 near the bottom of said bath, and maintaining the upper portion of the still above the surface of the bath under a partial vacuum.

4. The process of increasing the condensable constituents of a hydrocarbon gas which 30 consists in passing the gas through molten metal and cracking said gas by the heat of such molten metal.

5. The process of treating hydrocarbons 35 which consists in introducing them on to the surface of molten metal and commingling, with the resulting vapors, gases passed through the molten metal.

6. The process of distilling hydrocarbons 40 which consists in bringing them in contact

with molten metal, and producing a partial vacuum by exhausting the upper part of a still contained in the molten metal.

7. The process of altering the composition of petroleum distillates which consists in 45 passing them through molten metal contained in a still and producing a partial vacuum by exhaustion at the upper part of the still.

8. The process of altering the composition 50 of petroleum distillates which consists in passing them through molten metal and under pressure controlled by the height of the molten metal.

9. The process of altering the composition 55 of petroleum distillates which consists in introducing them into a bath of molten metal below the surface of said metal, applying sufficient pressure to the distillates during the introduction to overcome the hydrostatic pressure of the molten bath and maintaining a partial vacuum in the still above the bath by exhaustion.

10. The process of altering the composition 60 of petroleum distillates which consists in passing them through molten metal and thereafter compressing and condensing the products of the cracking operation.

11. The process of altering the composition 65 of petroleum distillates which consists in introducing the distillates below the surface of a molten metal bath under sufficient pressure to overcome the hydrostatic pressure of the molten metal, maintaining a partial vacuum above the surface of the molten 70 metal bath and condensing the products of the cracking operation.

In testimony whereof I have signed my name to this specification.

AUGUSTE J. PARIS, JR.
